UNITED STATES PATENT OFFICE

DARIO ROBERTI, OF SPRINGFIELD, MASSACHUSETTS

COMBINATION LOCK

Application filed December 19, 1929. Serial No. 415,265.

This invention relates to combination locks which may be adapted to a wide variety of uses, such as for suit cases, trunks, doors, drawers, etc. In the particular adaptation 5 thereof hereinafter described, the invention is embodied in an ignition switch for automobiles whereby the switch may be locked in its open condition.

A feature of the invention is that the entire lock mechanism is carried in a case which may be dismounted from its support on the dash or instrument board of a car at such times as the switch is unlocked but is retained securely in position while the switch is locked. 15 Such removal of the lock mechanism makes easy the inspection and change of combination for the lock when desired.

The invention further resides in the combination and arrangement of parts for accomplishing in a simple and effective manner the desirable functions of a combination locked switch or other locking member.

Referring to the drawings which show a preferred embodiment of the invention:

25 Fig. 1 is a view of the entire lock assembly as it appears from the front, with the face plate in position and showing in dotted lines the lock case;

30 Fig. 2 is a side view of the lock case showing the walls of the receptacle and face plate therefor in section;

Fig. 3 is a bottom end view of the lock case with the cover closed;

35 Fig. 4 is a side view of the lock case with the cover thereof in open position to show the mechanism contained within the case. (In this view, the switch is closed and the lock bolt is in its rearmost position unlocked.)

40 Fig. 5 is a similar view with the switch open, the lock bolt being in forward position and locked;

45 Fig. 6 is a longitudinal section through the lock casing with the cover closed, taken in the plane indicated by the line A—A of Fig. 4;

Fig. 7 is a detail section similar to that of Fig. 6 showing the racks in lock releasing position;

50 Fig. 8 is a transverse section through the

lock case with the cover closed, taken along the line indicated at B—B in Fig. 5;

Fig. 9 is a detail section through the cover of the case along line C—C of Fig. 4;

Fig. 10 is a detail section along line D—D of Fig. 4 showing the throw off device for the holding pawls; and

Fig. 11 is a similar view showing the throw off device in thrown out position.

Referring more particularly to the drawings, the lock mechanism is mounted and contained within a case made up preferably in a box like body 1 with a cover member 2 hinged at 3 along an upper side corner of said box. The case is intended to be mounted in a receptacle, the walls of which are indicated at 4 in Fig. 2, said receptacle being provided in the usual instrument board or other support in an automobile. The receptacle 4 is open at the front and there is preferably provided a face plate 5 over the front side of the box, which face plate is designed to overlap the edges of the receptacle 4 when the case is in position as indicated in Fig. 1. Mounted in a suitable manner upon the automobile adjacent the receptacle 4 is a switch contact device 6 adapted to coat with a switch tongue 7 of the lock mechanism for closing and opening the usual ignition circuit of the car.

In the particular embodiment of the invention herein described and shown, the lock mechanism is designed for locking the switch tongue 7 when the latter has opened the switch so as to prevent the use of the car until the combination of the lock is set for release. As will be evident for such a purpose, the switch tongue 7 will therefore be locked in its forward or lockable position and unlocked in its rearward or unlockable position. It will be understood of course that an opening is provided through the receptacle opposite the switch member 6 for allowing the switch tongue 7 to extend therethrough in coacting with said switch member.

Referring particularly to Fig. 4, there is mounted for sliding movement upon the side of the box 1, the lock bolt 8 formed preferably as an angle member with a vertical projecting wall 8a having a series of spaced

notches 8b therein (see Figs. 6, 7 and 8). The rear end of the lock bolt has integral or fastened thereto the switch tongue 7 previously mentioned.

5 The cover 2 of the case is formed with a plurality of dove tailed channels 9, as shown in Fig. 8, for receiving therein a plurality of toothed racks 10 which are slideable in the channels and normally impelled toward the 10 lower end of said channels by return springs 11, also mounted in said channels, there being a separate return spring for each of the racks 10 as shown. The racks 10 are retained from moving endwise out of their respective 15 channels by a keeper 12 hinged to the cover at pivots 13 and 14, as shown in Fig. 4. Projecting pins 15 and 16 fixed to the end of the cover 2 are engageable by a latch 17 mounted on the end of the box 1 and impelled by a 20 spring 18 for latching said cover in closed position. A bent wire spring 19 is mounted within the box 1 (as shown in Figs. 4 and 6) in a manner acting to throw the cover open when unlatched.

25 As shown in Fig. 8, when the cover 2 is closed the racks 10 lie in the notches 8b of the lock bolt 8. In other words, the racks 10 are arranged in intersecting relation with the lock bolt 8 when the cover is closed and 30 thus act normally to lock or prevent any transverse movement of the lock bolt 8. It will be understood of course that the cover 2 cannot be closed unless the lock bolt is forward, viz., switch open position. The rack 35 bars 10, however, are each formed with an arbitrarily located notch 20 which, when they come into registration with the notches 8b of the lock bolt, free the latter for a longitudinal movement. In this way the lock bolt 40 may be unlocked and the switch closed.

A coil spring 25 is mounted on the box 1 tending to throw the lock bolt 8 rearwardly for closing the switch, and a handle stem 26 fixed at one end of said lock bolt extends to 45 the outside of the case through the face plate 5 and is provided with a finger knob 27 for its operation.

The racks 10 are designed to be independently operated for bringing their notches 20 into registration with the notches 8b of the lock bolt and it will be understood that said notches 20 may be located at different distances from the ends of the racks 10 so that the latter will each require a different amount 50 of travel to bring said notches 20 into registration with the notches 8b. The different lengths of movement for the racks 10 will be integral multiples of a step by step operation as determined by the combination, so-called, of the lock. The several racks 10 are preferably operated with a step by step movement so that each step may be counted and different combinations of said counted 55 steps will be available for releasing the lock. The means for operating the racks 10 each

independently of the other comprises a selectively operated pinion 21 fixed to a sliding tubular shaft 22 having a finger knob 23 at its outer end for rotating the same. The shaft 22 is telescopically mounted for sliding movement upon an inner shaft 49 fixed to the box 1. The tubular shaft 22 has formed at spaced points along its length annular grooves 24 adapted to be engaged by a detent spring 50 and thus position the pinion 21 70 for mesh with one or the other of the several racks 10. The detent spring 50 is preferably mounted between the front face plate 5 and the wall of the box 1 and in a recess in the face plate, as shown in Fig. 2.

80 A separate holding pawl, such as 28, is provided for each of the racks 10 and these several holding pawls are preferably formed as a bent spring member anchored at one end upon a common holding bar 29 (see Figs. 6 85 and 7). The holding bar 29 is pivotally mounted upon a cross pin 30 fixed in the box and has laterally extending therefrom at one end a segment arm 31, the outer end of which is formed into a gear segment 32 (see Figs. 10 90 and 11). A compression spring 33 normally tends to keep the gear segment 32, bar 29, and associated spring pawls 28 in upper position, as shown in Figs. 7 and 10, whereby said spring pawls 28 ride into engagement with 95 the teeth of the several racks 10 and act to hold said racks after each step by step movement of the latter. The gear segment 32 is located at the rear side of the box 1 or at the left side (Fig. 4) and when it is desired to 100 release the racks 10 from their holding pawls 28 for being restored to initial position by their several return springs 11, the selective pinion 21 is pushed inwardly to its innermost position for meshing with said segment gear 105 32. Thereupon the knob 23 is turned clockwise and the pinion 21 will swing the gear segment 32 downwardly against the force of its spring 33, which movement acts to withdraw the several holding pawls 28 collectively 110 from their engagement with the racks 10.

A clicking detent is also preferably provided for engagement with the selective pinion 21 for counting by sound the different step by step movements of the latter, and this detent preferably consists of a wide blade 34 pivoted on the pin 30 so as to engage the pinion 21 in all of its positions of adjustment. A spring 35 fixed to the box 1 tends to keep the clicking detent 34 in engagement with said pinion 21 and a cross pin 36 mounted in the box serves as a stop for said clicking detent 34. 115

120 A finger operated release latch is also provided for the lock bolt 8 whereby when the combination is set in unlocking condition, the combination may be opened and closed freely. This mechanism comprises a latching dog 37 carried on a swinging arm 38 pivoted at 39 in the box 1. The forward end of the arm 38 has fixed thereto a finger knob 40 positioned 125

on the outside of the face plate. A prong 25a of the spring 25 tends to keep said arm 38 and dog 37 in lowered position (see Fig. 4). A lower reduced end of the dog 37 extends 5 through a guide wall 41 fixed in the box 1 and is adapted to take within a notch 42 of the lock bolt 8 and hold the same in forward position. Thus when the lock bar is retracted by the knob 27, it will be held in retracted position by the dog 37, and the raising of knob 40 will act to release the dog and permit rearward movement of the lock bolt 8 and its switch tongue 7. The condition for allowing a switch closing movement of the lock bolt is 10 that the combination may be properly set. While this condition continues, the switch may be freely opened and closed by successively pulling out knob 27 and raising knob 40.

20 The present lock case, together with its locking mechanism, is designed to be removably mounted within its receptacle 4 so that it may be dismounted completely when desired for inspection and change of the combination. For this purpose, retaining latches 43 and 44 are provided, one for the upper end of the case and one for the lower end of the case and preferably mounted adjacent the front wall of said case, as shown in Fig. 4. 25 These retaining latches 43 and 44 are slidably mounted on said case front wall and adapted to protrude from each end of the case for taking into keepers provided therefor in the receptacle. Each retaining latch 43 and 30 44 is preferably formed with two outer projecting portions, such as 43a shown in Fig. 3. The inner ends of said latches 43 and 44 are connected together by a return spring 45 tending to keep them in withdrawn position. 35 The inner ends of said latches 43 and 44 are also provided with wedge feet 46 and 47 arranged to coact with a wedge shaped front end 48 of the lock bolt 8 whereby when said lock bolt is retracted, end 48 will spread apart 40 the feet 46 and 47 and throw the latches 43 and 44 into their protruding position for locking the case within its receptacle. It will be noted, however, that whenever the lock bolt is not retracted (i. e., in switch closing 45 position), the retaining latches 43 and 44 are inactive and the lock case as a whole may then be withdrawn from its receptacle; but that whenever the lock bolt 8 is in retracted position (i. e., in switch open position), the case 50 is then locked in its receptacle and cannot be removed therefrom.

It will be understood from the foregoing description that in use the present lock mechanism can be set for any particular combination by changing the position of the notches 20 in the racks 10. This may be conveniently accomplished by releasing the keeper 12 and either interchanging the racks 10 in their channels 9 or by the introduction of new racks 55 having differently located notches 20. When

the combination is set for releasing the lock as above described, the knob 40 may be operated to close the switch. When it is desired to open the switch and lock it open, knob 27 is first pulled to retract the lock bolt 8 and 70 knob 23 is then moved to engage pinion 21 with the gear segment 32 and release the holding pawls 28, whereupon all the racks will be restored, upsetting the combination and requiring it to be reset before the lock can be 75 released.

While I have described in detail the preferable embodiment of the invention, it will be understood that various modifications and changes can be made therein without departing 80 from the invention as defined in the accompanying claims.

Claims:

1. In a combination lock in combination, a lock bolt movable between lockable and unlockable positions, a plurality of separately operated racks mounted in intersecting relation with said lock bolt for locking the same in its lockable position, each of said racks having an arbitrarily positioned notch for 90 freeing said lock bolt, selective means for operating said racks comprising a sliding pinion adapted to engage with any one of several racks, a return spring and a holding pawl associated with each rack. 95

2. In a combination lock in combination, a lock bolt movable between lockable and unlockable positions, a plurality of separately operated racks mounted in intersecting relation with said lock bolt for locking the same in its lockable position, each of said racks having an arbitrarily positioned notch for 100 freeing said lock bolt, selective means for operating said racks comprising a sliding pinion adapted to engage with any one of several racks, a return spring and a holding pawl associated with each rack, and a clicking detent for said pinion. 105

3. In a combination lock in combination, a lock bolt movable between lockable and unlockable positions, a plurality of separately operated racks mounted in intersecting relation with said lock bolt for locking the same in its lockable position, each of said racks having an arbitrarily positioned notch for 110 freeing said lock bolt, selective means for operating said racks comprising a sliding pinion adapted to engage with any one of several racks, a return spring and a holding pawl associated with each rack, means operated by said selective means for throwing out said holding pawls collectively and thereby permit restoration of said racks by the return springs. 115

4. In a combination lock in combination, a lock bolt movable between lockable and unlockable positions, a plurality of separately operated racks mounted in intersecting relation with said lock bolt for locking the same in its lockable position, each of said racks 120

having an arbitrarily positioned notch for
freeing said lock bolt, selective means for op-
erating said racks comprising a sliding pinion
adapted to engage with any one of several
racks, a return spring and a holding pawl
5 associated with each rack, means operated
by said selective means for throwing out said
holding pawls collectively and thereby per-
mit restoration of said racks by the return
springs, said means comprising a throw-out
10 bar common to said holding pawls and hav-
ing a gear sector adapted to be engaged by
said pinion.

In testimony whereof I have affixed my sig-
nature.

DARIO ROBERTI.
